UNITED STATES PATENT OFFICE.

ALBERT H. MORTON, OF LOWELL, MASSACHUSETTS.

PICK COUNTER FOR LOOMS.

Application filed April 29, 1922. Serial No. 557,292.

To all whom it may concern:

Be it known that I, ALBERT H. MORTON, a citizen of the United States, residing at Lowell, in the county of Middlesex and State of Massachusetts, have invented certain new and useful Improvements in Pick Counters for Looms; and I do hereby declare the following to be a full, clear, and exact description of the invention, such as will enable others skilled in the art to which it appertains to make and use the same.

The present invention relates to an improvement in pick counters for looms.

A great many attempts have been made to apply pick counters to looms, but every such attempt, so far as I am aware, has ultimately failed because the excessive vibration of the loom in operation has eventually destroyed, worn out or rendered inoperative such counters. Pick counters have been applied to looms made of the most sturdy construction, and great strength and durability, but the excessive vibration and racking due to the operation of the loom has worn them out or destroyed them in a comparatively short space of time. The object of the present invention is to produce a pick counter for looms of a new construction such that the vibrations and blows to which the loom is subjected are prevented from being transmitted to the pick counter by supporting the pick counter from the loom frame by resilient means. To the above ends the present invention consists in the pick counter hereinafter described and particularly defined in the claims.

In the accompanying drawing illustrating the preferred form of the invention, Fig. 1 is a perspective view from the rear, showing a part of the loom with the improved pick counter in position thereon; Fig. 2 is a front elevation of the pick counter, showing the channel of the frame to which it is attached in section; and Fig. 3 is a bottom plan view of the pick counter bracket.

The illustrated embodiment of the invention is described as follows: The pick counter 1 is mounted on a bracket 2, secured to the arch 3 of the loom. It is connected by a flexible shaft enclosed in an armored casing 4 with the lay shaft of the loom, a hand wheel 5 on the lay shaft being shown. The

pick counter proper 1 may be of any usual or preferred construction. In the illustrated embodiment of the invention it is provided on one end with a boss 10, to which its supporting bracket is attached, and on the other end with a boss 11, to which the flexible shaft and armored casing are attached. The bracket 2 consists of a strip of flexible metal fastened at one end by means of rivets 12 to the stud 13, the shank 14 of which penetrates a hole in the flange 15 of the arch 3 of the loom. The shank 14 is secured in place by a nut 16. The other end of the bracket is attached to the boss 10 of the counter by means of the cap screw 17. The bracket 2 is twisted between its ends so that lateral vibrations will be taken care of by the flat in one plane, while longitudinal vibrations may be taken care of by the flat in the other plane. Thus the vibrations both lateral and longitudinal of the loom frame are only transmitted to the pick counter by means of this resilient bracket, which absorbs and reduces and modifies the effect of such vibrations and blows upon the pick counter.

It is to be understood that the present invention is broad and generic in character, and that it includes within its purview any form of pick counter which is supported from the frame of the loom by resilient means operating to prevent the direct transmission to the counter proper of the blows, vibrations or shocks to which the frame is subjected in operation.

Having thus described the invention, what I claim is:

1. A pick counter for looms, comprising a counter proper, and a resilient support for attaching the counter to the frame of a loom, said counter having different portions for absorbing the lateral and longitudinal vibrations of the loom frame.

2. A pick counter for looms, comprising a counter proper, and a resilient supporting member for attaching the counter to the frame of a loom, said supporting member having separate portions thereof disposed in different planes for respectively absorbing the lateral and longitudinal vibrations of the loom frame.

ALBERT H. MORTON.
